Attorney, Agent, or Firm—George J. Primak

[57] **CLAIM**

The ornamental design for flower bag, as shown and described.

DESCRIPTION

FIG. 1 is a perspective view of the invention;
FIG. 2 is a front view of the invention;
FIG. 3 is a back view of the invention;
FIG. 4 is a side view of the invention;
FIG. 5 is a top view of the invention; and,
FIG. 6 is a bottom view of the invention.
